UNITED STATES PATENT OFFICE.

JAMES W. KELCH AND JAMES J. SUNDAY, OF DETROIT, MICHIGAN, ASSIGNEES, BY DIRECT AND MESNE ASSIGNMENTS, TO KELCH VENTILATING HEATER COMPANY, A CORPORATION OF MICHIGAN.

HEATER FOR AUTOMOBILES.

Application filed July 27, 1925. Serial No 46,411.

This invention relates generally to heating apparatus for motor vehicles and consists of certain novel features of construction, combinations and arrangements of 5 parts as will be more fully described and particularly pointed out in the appended claims.

In the accompanying drawing:

Figure 1 is a fragmentary side elevation 10 of a vehicle with a heater embodying our invention attached thereto.

Figure 2 is an enlarged fragmentary vertical longitudinal sectional view through the heater.

15 Figure 3 is a sectional view taken on the line 3—3 of Figure 2.

Figure 4 is a detail side elevation of the front header.

Referring now to the drawing in which 20 like characters of reference designate corresponding parts throughout the several views, the numeral 1 designates a motor vehicle having an engine exhaust conduit 2 to which the heater 3 embodying our invention is 25 preferably attached. As shown, the heater 3 is preferably provided with a core 4 and an outer shell or casing 5.

In order that the exhaust gases from the 30 motor of the vehicle may be used as the heating medium, the casing or shell 5 is preferably cylindrical in form and is provided at its opposite ends with funnel-shaped heads 6 and 7 respectively that are adapted to be sleeved upon aligned portions 8 and 35 9 respectively of the exhaust conduit 2. Thus, the tubular portions 6' and 7' of their heads constitute inlet and outlet ports for the exhaust gases. Any suitable means may be employed for conveying air from the atmosphere to the shell 5 and from the shell 40 to the body 11 of the vehicle. As shown, a suitable pipe 12 extends forwardly from the shell 4 adjacent to the forward end thereof and terminates in a flared portion 13, disposed adjacent to the fan 14 of the engine, while a second pipe 15 extends rearwardly 45 from the shell 4 adjacent to the rear end thereof and connects into a suitable air register 16 which may be located at any convenient place such as in the floor of the vehicle body.

In order that the exhaust gases from the engine will be directed through the shell 4 without mixing with the air discharged by

the conduit 12, the core 4 is preferably provided with two headers 19 and 20 respectively and a plurality of spaced straight tubes 21. As shown, the headers 19 and 20 are preferably disposed at opposite ends of the shell while the tubes 21 extend between these headers and are supported thereby. These tubes may be made of any suitable material such as copper or aluminum and are preferably arranged closer together at their rear ends so that the desired concentration of 55 heat may be obtained. To provide a strong and durable construction the tubes 21 are preferably brazed to the headers 19 and 20 respectively. Thus, the tubes 21 are not likely to work loose while the heater is in 60 use.

To prevent back pressure on the engine as well as objectionable noise, the forward header 19 is preferably provided adjacent 65 to its periphery with a series of rearwardly projecting substantially frusto-conical socket portions 22 and is provided at its center with a forwardly projecting conical portion 23. As shown, the conical portion 23 is in alignment with the tubular inlet port 6' of 70 the head 6 and is adapted to deflect the exhaust gases radially into the socket portions 22 which in turn discharge into the tubes 21.

In order that the shell 5 and core 4 of the heater may be easily and quickly assembled or taken apart, the header 19 is preferably clamped between the flanges 24 and 25 respectively of the head 6 and shell 5 by means of suitable bolts 26, while the header 20 is preferably bolted to an annular plate 27 that is clamped between the flanges 28 and 29 respectively of the head 7 and shell 5 by means of the bolts 30. To facilitate attachment of the heater to the exhaust pipe 2, the tubular portions 6' and 7' respectively 85 of the heads 6 and 7 are preferably clamped into position upon the portions 8 and 9 of the exhaust conduit by means of split collars 31. Thus, with this construction, the heater may be readily removed from the 90 conduit 2 and taken apart to be cleaned or repaired.

If desired, a suitable baffle 32 may be sleeved upon certain of the tubes 21 of the core approximately midway of the shell 105 5 for deflecting around the tubes the air discharged from the conduit 12. Thus, a better circulation of the air is obtained within the

shell 5. If desired, a suitable cover of asbestos (not shown) may also be provided for the shell to insulate the same from the cold.

5 In use, air from the atmosphere will be discharged from the conduit 12 into the shell 5 where it will be heated by the exhaust gases passing through the tubes 21 of the core and will be subsequently discharged 10 into the conduit 15 leading to the register 16. The exhaust gases from the engine will be discharged by the forward portion 8 of the exhaust conduit against the conical portion 23 of the header 19 and will be deflected 15 radially by said conical portion into the frusto-conical socket portions 22 which in turn discharge into the tubes 21, consequently the gases will be substantially uniformly distributed into the tubes 21. As 20 a result all of the tubes will be heated substantially equal.

Inasmuch as the projection 23 is an acute cone it will be apparent that it will not retard the flow of gases but will serve effectively to direct the gases into the frusto-conical portions 22. It will also be noted that the inner sides of the frusto-conical portions 22 form a direct continuation of the sides of the projection 23, hence the exhaust 30 gases will have an uninterrupted passage from the projection 23 into the tubes 21. As a result back pressure will not be built up on the motor of the vehicle.

While it is believed that from the foregoing description the nature and advantages 35 of our invention are readily apparent, we desire to have it understood that we do not limit ourselves to what is herein shown and described and that such changes may be 40 sorted to when desired as fall within the scope of what is claimed.

What we claim as our invention is:

1. A heater for motor vehicles including a shell having inlet and outlet ports for the 45 exhaust gases of the motor, a plurality of tubes extending longitudinally of the shell between said inlet and outlet ports, and means for directing the exhaust gases into said tubes, said means including a plate having frusto-conical portions connected to the inlet ends of said tubes and having a projection in alignment with the inlet port aforesaid for deflecting said gases into said frusto-conical portions.

55 2. A heater for motor vehicles including a tubular shell having laterally opening inlet and outlet ports for air and having substantially aligned inlet and outlet ports for the exhaust gases of the motor, a plurality of 60 tubes extending longitudinally of the shell between said gas inlet and outlet ports, and a transversely extending header within the shell having rearwardly extending substantially frusto-conical socket portions secured 65 to the inlet ends of said tubes and having

means in alignment with the inlet port for directing the exhaust gases into said socket portions.

3. A heater for motor vehicles including a shell having laterally opening inlet and outlet ports for air and having aligned inlet and outlet ports for the exhaust gases of the motor, a plurality of tubes extending longitudinally of the shell between said gas inlet and outlet ports, and a header within said shell having means for directing the exhaust gases into said tubes and having additional means for deflecting toward the last mentioned means the exhaust gases discharged into said shell through said inlet port. 75 80 85

4. In a heater for motor vehicles, the combination with a tubular shell, and a core within the shell including a series of tubes extending longitudinally of the shell, and a one piece header for the core having rearwardly projecting socket portions connected to the inlet ends of the tubes and having means intermediate said socket portions for deflecting exhaust gases into said socket portions. 85 90 95

5. A heater for motor vehicles including a core, and an outer shell therefor, said core including spaced headers, and tubes extending longitudinally of the shell between said headers, said shell having an inlet at one end 95 for the exhaust gases from the motor of the vehicle, and the adjacent header of said core having a forwardly projecting conical portion in alignment with said inlet for deflecting toward said tubes the exhaust gases discharged into said shell through said inlet and having rearwardly projecting socket portions concentric with said inlet for directing the deflected gases into said tubes, the inner walls of said socket portions forming a direct continuation of the sides of said conical portion so that the exhaust gases will have uninterrupted passage from said projection into said tubes. 100

6. A heater for motor vehicles including a tubular shell having laterally opening inlet and outlet ports, for air, heads at the opposite ends of the shell having substantially aligned inlet and outlet ports for the exhaust gases of the motor, a tube extending longitudinally of the shell between said inlet and outlet ports, and means for directing the exhaust gases into said tube including a transversely extending plate within the shell having a substantially frusto-conical portion connected to the inlet end of the tube and having a projection in alignment with the inlet port aforesaid for deflecting said gases into said frusto-conical portion. 110 115 120

7. In an air heater for vehicle bodies, the combination with a tubular shell having lateral inlet and outlet ports for air, and heads at the opposite ends of said shell provided with substantially aligned inlet and outlet ports for exhaust gases, of a core unit with- 125 130

in the shell including a plurality of substantially straight lengths of tubing arranged in substantial alignment with the exhaust inlet and outlet ports, and supports for said tubing including a sheet metal header extending transversely of said shell and having rearwardly extending substantially frusto-conical socket portions secured to the forward ends of said tubing for directing the exhaust gases from said gas inlet port into said tubing.

In testimony whereof we affix our signatures.

JAMES W. KELCH.
